UNITED STATES PATENT OFFICE.

WILLIAM K. LAVIS, OF LA GRANGE, ILLINOIS, ASSIGNOR OF ONE-HALF TO MORGAN K. BARNUM, OF LA GRANGE, ILLINOIS.

ROOF-FRAME FOR FREIGHT-CARS.

1,004,044.

Specification of Letters Patent. Patented Sept. 26, 1911.

Application filed June 28, 1910. Serial No. 569,274.

To all whom it may concern:

Be it known that I, WILLIAM K. LAVIS, a citizen of the United States, residing at La Grange, in the county of Cook and State of Illinois, have invented certain new and useful Improvements in Roof-Frames for Freight-Cars, of which the following is a specification:

The principal object of my invention is to provide a new and improved roof frame adapted to be used in the construction of cars and particularly in the construction of freight cars.

Another object is to provide a non-racking roof framework suitable to support and secure an ordinary freight car roof.

Another object is to provide a strongly braced, light weight, freight car roof frame structure.

Still another object is to provide a light and strong freight car roof frame suitable for use in connection with the peculiar jointed metal plate roofing described in my Patent No. 954,194 of April 5, 1910. I also desire to provide a structural metal car roof frame of great strength and durability.

These objects and others will be made apparent in the following specification and claims, taken in connection with the accompanying drawings showing a preferred embodiment, in which—

Figure 1 is a top plan view of a finished car roof with the running board and part of the roof plates and bars broken away so as to show more fully the nature of the structure. Fig. 2 is a perspective view of one of the several braced metal cross bars each of which is known as a carline. Fig. 3 is a perspective view of the end fastening of one of the four similar branches of a carline. Fig. 4 is a cross sectional view of the roof frame on the line 4 of Fig. 1 with the covering and running board removed and shows particularly one of the side plates, one of the carlines, the ridge pole, and part of the longitudinal roof bars known as purlins. The ridge pole and purlins here shown are each composed of a channel bar inclosing a wooden filler-block. Fig. 5 is a cross sectional view similar to Fig. 4 except the inverted position of the ridge pole and slight minor details. Fig. 6 is also a cross sectional view similar to Fig. 4 except the inverted position of the ridge pole and purlins, which in this the most preferred em-

bodiment are plain channels devoid of filler-blocks. Fig. 7 is a top plan view of a portion of the roof frame showing how a carline is attached to the purlins and ridge pole of the embodiment shown by Fig. 6. Fig. 8 is an upper end corner of a vertical longitudinal section showing the relative positions of the end plate, ridge pole and end sheathing. Fig. 9 is a vertical transverse section along the line 9 of Fig. 10 showing the complete roof including the running board and embodying the frame shown in Fig. 11. Fig. 10 is a vertical longitudinal section along the line 10 of Fig. 9. Fig. 11 is a vertical cross section of the roof frame only along the line 9 of Fig. 10 and shows a carline of metal and purlins and ridge pole made of wood alone.

In all the views like reference numerals refer to like parts.

Referring to the preferred embodiment shown in Fig. 1, the roof structure consists generally of a closed covering mounted on a structural iron framework. The covering here shown consists of sheet metal plates. The plates at the end are marked 47 and the intermediate plates 46, the said plates all being locked together by upturned edges and the ridge and cross sheaths 48 and 49, respectively, essentially as per my previous patent aforesaid. This covering is attached to and is supported by the frame composed chiefly of structural iron as shown.

The improved frame which I have now invented to use particularly for supporting freight car roofs and the like is especially constructed for lightness and strength. It consists chiefly of two side plates 16, two end plates 15, a ridge pole 23, a set of carlines 1, and a set of purlins 29.

The peculiar inherent and integral bracing structure of the carlines is one of the principal features of my invention. One of these carlines is shown in detail by Fig. 2, in which 1 is the complete carline, 2 either one of two similar and complementary component angle bars that together constitute a carline, 2' the top flange of bar 2, 2" the side flange of bar 2, 4 the horizontal middle portion of bar 2, and 5 is one of a group of clamping elements, preferably rivets, through the flanges 2" to fasten together the two complementary bars 2 at the central portion 4 of the bars that thus assembled constitute a carline. The downwardly in-

clined outer portions of the component angle bars 2 are marked 6. The point where each bar 2 diverges from the other and bends downward is indicated by numeral 7. Each 5 of the bars 2 has its end split between the two flanges 2' and 2'', the top flange 2' having its end 8 turned to a horizontal position and the side flange 2'' having its end 9 turned transversely and toward the complementary member. The point where the flange ends 8 and 9 bend from alignment with the adjacent bar body and divergent from each other is marked 10. The flange end 8 is perforated by a hole 11 and flange 15 end 9 is provided with holes 12. The inclined portion of flange 2' is provided with holes 13 and the horizontal part of flange 2' is provided with a hole 14. These holes are adapted for engagement with bolts, rivets or 20 the like for fastening to other parts of the frame and roof.

The main outer framework for the roof consists of two side plates 16 and two end plates 15 fitted together in rectangular shape. 25 On the upper side of each side plate are furnished filler-blocks 17 so as to provide an inclined upper surface to engage the roof covering. These filler-blocks are provided with spaces 18 to admit the flange ends 8 for fastening to the side plates 16 by means 30 of the bolts 3, as shown by Fig. 3. Each filler-block 17 has a flat horizontal under side 21 to engage the top of the side plate 16, an inclined upper surface 20 to engage with 35 the roof and a vertical inner face 19.

In Fig. 1 bolts 22 are shown for fastening the flange ends 9 to the plates 16. The bolts 3 are also here shown. The ridge pole 23 is shown centrally located and supported on 40 the carlines 1, where secured by the bolts 45. In this embodiment shown by Figs. 1 and 9 these bolts 45 extend downward through the running board 24, saddle block 25, ridge sheath 49, ridge pole 23, and carline flange 2'. 45

I prefer generally to use separate means 42 for fastening the ridge pole to the carlines as shown in Figs. 4, 5, and 6 and then the bolts for fastening the running board, saddle block and ridge sheath to the ridge 50 pole may be distributed along the ridge irrespective of the carlines. The purlins 29 are suitably distributed on each side of the ridge pole and fastened by suitable means such as bolts or rivets 30 to the carline bars 2.

55 The ridge pole 23, which in its preferred embodiment, as shown in Fig. 6, consists chiefly of a channel bar, has its side flanges 40 cut away at the ends and the end 43 of its web 39 turned down at the point 37 over the 60 end plate 15 and secured by suitable means, such as bolts through the holes 44, shown in Fig. 4, the end sheathing 38 being recessed to receive it as shown in Fig. 8. The purlins are also formed and secured at their ends in 65 a similar way. Several embodiments of

ridge pole and purlin construction are shown by Figs. 4, 5, 6 and 11, Fig. 6 showing the one I prefer.

The ridge pole and purlins shown in Fig. 6 each consist of a metal channel bar only 70 and in Fig. 11 they are made of wood only while in Figs. 4 and 5 they each consist of a channel bar containing a filler-block of wood.

In Fig. 4 one end of a carline 2 is shown attached to the side plate 16 and supporting 75 the wood-filled channel bars constituting the purlins 29 and ridge pole 23. Each purlin channel 31-32 is shown with its flanges 32 cut away and its web 31 turned downward at the end 35 and provided with perforations 36 to engage with means for fastening to the end plate 15 in a manner similar to that by which the web of the ridge pole channel is turned downward at its end 43 and provided with perforations 44, for bolts 85 or the like as aforesaid. The purlin filler-block is marked 33 and ridge pole filler-block 41.

Fig. 5 is similar to Fig. 4 except that the ridge pole is inverted so that its channel 90 flanges turn downward instead of upward.

The embodiment of Figs. 6 and 7 differs from those of Figs. 4 and 5 only in that the ridge pole and purlin channels are all devoid of filler-blocks and all have their 95 flanges turned downward, the said flanges being trimmed away at the points of engagement with the end plates and carlines so as to give the channel webs direct bearing on the cross elements. The flange 2' of the 100 carline then fits in the notches 34 in the purlin flanges 32 and in similar notches 56 in the ridge channel flanges 40.

Fig. 11 showing the use of plain wooden purlins and ridge pole is similar to Fig. 4 105 except that all channel bars are omitted. This provides lightness of construction where the greater strength of channel irons is not required.

Figs. 9 and 10 show longitudinal and 110 transverse sections respectively of the roof assembly. Fig. 9 shows the roof framework of Fig. 11 in conjunction with the sheet metal roofing and running board as described in my previous patent aforesaid. 115 The metal roof plates 46 with their upper inward edges 46' hooked and nearly abutting and with their lower outer edges resting on the side plate filler blocks 17 are shown in Fig. 9. The said inner hooked 120 edges 46'' are locked by means of the ridge sheath 49. The side edges 46' are also similarly hooked and locked by the cross sheaths 48. The outer end of each cross sheath is secured by a downwardly turned end 55 125 fastened to the side of the car by a bolt 54 as shown in Figs. 1 and 9. Each end 53' of the ridge sheath 49 is likewise turned down and fastened by a bolt 53.

All outer edges of the roof plates 46 and 130

47 adjacent to the edge of the roof are clamped in place by the clips 50—51 and 50'—51 the latter being used at the roof corners. Each clip has tongues 51 to engage 5 the roof plates and a main downwardly turned part 50 or 50' respectively equipped with screws 52 or the like to engage with the side of the car.

A running board is provided as shown in 10 Figs. 9 and 10. This consists of the several strips 24 attached to saddle blocks 25 placed across the ridge sheath 49. Each block is fitted on its under side with a middle surface 27 to engage and rest on the ridge 15 sheath 49, and with inclined surfaces 26 to engage with and rest on the cross sheaths 48. Bolts 45 are provided to extend downward through the center of the running board 24, the saddle block 25, sheath 49 and ridge pole 20 23, thus to lock the parts securely together.

While I have herein shown and particularly described some embodiments of my invention, I do not wish to limit myself to the precise constructions as herein shown 25 and particularly described as many modifications may be made by those skilled in the art without departing from the spirit of my said invention.

Having thus described my invention I 30 claim:

1. In a car roof, the combination with a set of carlines, each comprising two complementary angle-bars, each angle-bar having a vertical flange and a flange extending outwardly at a right angle from the upper edge of said vertical flange, the vertical flanges of said two angle bars lying in parallel relation for a short distance upon each side of the longitudinal center of each carline and 35 there secured together, said angle bars upon the opposite sides of such central portion inclining downward and diverging from each other; of a set of purlins, each secured to two divergent branches of each of said carlines.

2. In a car roof, the combination with a set of X-shaped carlines, of a set of purlins,

each comprising a channel-bar having flanges projecting downward from the central web thereof, said flanges of each channel bar being cut away at suitable intervals to fit upon the opposite sides of two branches of each of said X-shaped carlines and to permit the webs of said channel-bars to rest directly upon said carlines. 55

3. The combination with a set of carlines each comprising two complementary angle-bars, each angle-bar having a vertical flange and a flange extending outwardly at a right angle from the upper edge of said vertical flange, the vertical flanges of said two angle bars lying in parallel relation for a short distance upon each side of the longitudinal center of each carline and there secured together, said angle bars upon the opposite sides of such central portion inclining downward and diverging from each other; of a set of purlins, each comprising a channel-bar having flanges projecting downward from the central web thereof, said flanges of each channel-bar being cut away at suitable intervals to fit upon the opposite sides of two branches of each of said carlines and to permit the webs of said channel-bars to rest directly upon said carlines. 70

4. In a roof frame, a carline composed of two similar and complementary angle bars 2 fastened together back to back at the middle portion 4 by rivets 5 through the downwardly extending flanges 2'', the said bars being bent divergently and diagonally downward at the point 7 toward the four ends where the flanges are separated and divergently bent at the point 10, the flange 2' being bent to a horizontal position and the flanges 2'' to a transverse inturned position, suitable perforations being provided for bolts and the like. 80

In testimony whereof, I have subscribed my name.

WILLIAM K. LAVIS.
